CABLE SOCKET APPLYING TOOL AND
METHOD

John W. Bair, Strasburg, Pa.

Application August 30, 1930, Serial No. 478,922
Renewed October 29, 1932

20 Claims. (Cl. 140—71)

This invention relates to a machine or tool and method for preparing the ends of wire cables and applying a socket or other anchoring tip thereto, and the invention has as its primary object 5 economy in time and labor.

In describing my invention in detail, reference will be had to the accompanying drawings, wherein like characters denote like or corresponding parts throughout the several views, and in 10 which:—

Figure 1 is a top plan view of the machine embodying the invention, the component units of the machine being illustrated in the relative positions which they will occupy on the first step of 15 the operation of treating a cable end to apply a tip of the specific sort generally called "a socket".

Figure 2 is a similar view illustrating the second step in the method and illustrating, partly in section, additional units which are employed 20 in this step.

Figure 3 is a view partly in top plan and partly in section and illustrating the next step in the method.

Fig. 3a is an elevation illustrating the last position.

Figure 4 is an end elevation of the machine. Figure 5 is a side elevation thereof.

Figure 6 is a view looking at that end of the machine opposite the end shown in Figure 4.

Figure 7 is a vertical transverse sectional view on the line 7—7 of Figure 1, looking in the direction indicated by the arrows, the cable end which is being treated being omitted, for the sake of clearness.

Figure 8 is a perspective view illustrating a contracting unit for contracting or bringing together the initially separated and relatively spread strands of the cable in another step of the method.

Figure 9 is a view in elevation of a pair of gripping members which are to be assembled with the unit shown in Figure 8.

Figure 10 is a top plan view of said members.

The numeral 1 indicates the base of the machine which is preferably of substantially oblong 45 rectangular form except at one end where it is somewhat widened and this base is supported at its ends by angle iron cross beams 2. The cable with its end broomed as hereinafter described is indicated in general by the reference letter C and 50 the machine includes a cable anchoring unit consisting of a cast iron head 3 which is secured by bolts 4 upon the base 1 at one end thereof and this head is provided with a vertical face 5 in which a recess 6 of semi-circular form is formed 55 and this recess confronts a similar recess 7 formed

in the corresponding face 8 of a head 9 which is provided at its lower side with outstanding flanges 10 mounted slidably in suitable channel guide members 11 bolted or otherwise secured upon the upper side of the base 1. A bearing member 12 60 is likewise mounted upon this end of the base and secured in place by bolts 13 and an adjusting screw 14 is fitted through a threaded opening in the bearing member and is provided with a polygonal head 15 for the application of a wrench 65 whereby it may be adjusted. The opposite end of this adjusting screw is swivelled as at 16 in that side of the head 9 opposite the side in which the recess 7 is formed, it being understood at this point that the screw 14 may be adjusted so as to adjust 70 the head 9. In this manner this portion of the cable is firmly anchored.

Before the cable is placed in the machine, a clamping member indicated as a whole at 17 is applied to prevent the separation of the wires from 75 extending inward beyond the point of such application. The member 17 comprises a pair of substantially semi-circular collar sections secured together by bolts 18. The cable, clamped and broomed, is placed in the machine and gripped and held between the heads 3 and 9 with the clamp 17 abutting against a contracting unit indicated as a whole by the numeral 19. This unit comprises a lower member 20 provided, intermediate 80 its ends, with a collar portion 21 and a member 22 is seated in a recess 23 formed in the upper side of the member 20 and secured in place by bolts 24 engaged through its ends and through the member 20 and has a collar portion 25 registering with the portion 21 of the member 20 and 85 the portions 21 and 25 are assembled as shown in Figures 7 and 8 of the drawings. The unit 19 will present a conical throat 26 through which the end of the cable, directly at the inner ends of its separated and spread wires, may be seated, and 90 the member 22 then secured in place. The minor end of the throat 26 is of substantially the same diameter as the wound cable and the taper of the throat is such as to correspond substantially to the manner in which the wires of the cable end are 95 spread as shown in Figure 1 of the drawings.

Openings 27 are formed in the ends of the member 20 of the contracting unit and rods 28 are mounted at their ends in these openings. Heads 29 on the end of said rods engage the 100 member 20. The other ends of the rods are threaded as indicated by the numeral 30 and are fitted through openings formed in the head 31 which is slidably mounted at its ends in pairs of guide rails 32 supported upon uprights 33 105 110

mounted upon the base 1, these pairs of uprights being arranged at opposite sides of the base 1 and being spaced by blocks 32^a and fastened by bolts 32^b, Figs. 5 and 6. An adjusting screw 34 is connected by a swivel connection, as at 35 with the head 31 and is threaded adjustably in a bearing 36 upon the said base 1, a polygonal head 37 being provided at the outer end of this screw for the application of a wrench whereby the screw may be rotated so as to adjust the head 31 longitudinally with respect to the rails 32. In order that the head 31 may be held in suitable positions of longitudinal adjustment with respect to the rods 28, nuts 38 are threaded onto the ends 30 of the said rods and engage the opposite sides of the head 31.

The tip which is to be applied to the end of the cable is indicated by the numeral 39. The tip illustrated is a common style of socket which comprises an exteriorly cylindrical body having a circumscribing flange 40 at one end and the body is formed, axially, with a conical bore 41 and the major end of this bore opens through that end of the body at which the flange 40 is formed and the bore is formed at its minor end with a conical flared seat 42.

In order that the tip 39 may be supported so that the separated and relatively spread wires of the cable end may be confined within the bore 41 thereof, in a step of the carrying out of the method which will presently be described, two hangers are provided and these hangers are indicated, one by the numeral 43 and the other by the numeral 44. The hangers are identical in construction so far as their body portions are concerned and each comprises an arcuate body portion 45 having a flange 46 which is provided with openings whereby the ends of the hanger may slide on the rods 28. Collars 47 on the rods are set by screws 48 on the rods in position to engage the hanger 44 in the position shown so as to push both its ends inward with the tip when the rods 28 are moved inward by the operating screw. The flange 40 of the tip similarly pushes the hanger 43 inward with the tip. The collars 47 will be adjusted in accordance with the length of the tip 39 to be supported. Each collar 47 is provided with a downwardly extending arm 49, at its inner side, and a grooved anti-friction wheel 50 is rotatably mounted at the lower end of each arm and travels upon the upper edge of a rail 51 mounted upon the base 1 and at the respective side of said base, it being understood that in this manner the rods 28 are reinforced and protected from any sagging due to the weight imposed upon them by the tip 39 and the cable C.

Likewise it will be evident that the hangers 43 and 44 are in this manner maintained in axial alignment with the conical bore 26 of the contracting unit 19.

The machine embodies another contracting unit which is indicated in general by the numeral 52 and this unit comprises a body 53 the main portion of which is exteriorly cylindrical and one end is exteriorly of conical form as indicated by the numeral 54 and adapted to seat in the major end of the bore 26 of the contracting unit 19 in carrying out another step of the method which will presently be more specifically described. The body 53 is likewise formed with a bore 55 (Fig. 2) and that end of the bore which opens through the tapered end 54 of the body 53 is flared and of conical form as indicated by the numeral 56. Otherwise the bore 55 is cylindrical in form and of a diameter to correspond

to the diameter of the cable throughout its wound portion. At its other end, the body 53 is formed with a flange 57 which is of annular form and extends about the corresponding end of the bore 55 and is exteriorly tapered to conical form so as to engage in the flared end 42 of the bore 41 of the tip 39. The unit 52 is formed in two sections as shown in Figures 9 and 10 of the drawings and in order to prevent any relative displacement of these sections when they are assembled about the cable, one of the sections is formed with sockets, indicated by the numeral 58 and the other with studs indicated by the numeral 59 which are adapted to engage in said sockets.

The term wire cable is used herein to include a variety of products commonly called cables, whether what is technically known as a strand (consisting of a number of individual wires bound or twisted together) or what is known as a wire rope (consisting of a number of such strands bound or twisted together); with or without a hemp center within the strands of the rope or within the wires constituting the strand, or within both.

In preparing the end of a wire cable for socketting the individual wires should be separated so as to be separately adherent to the molten zinc. Where there is a hemp center or centers, these are usually cut off when the ends of the wires are separated.

In applying the present invention, the first step is to clamp the cable at a determined point by the clamp 17 and to broom or separate the wires so that each stands out separately as indicated in Fig. 1. The wires are then thoroughly cleaned.

The machine is set in the position of Fig. 1 but with the cap 22 of the contracting unit removed and the gripping heads 3 and 9 separated. The clamped and broomed cable is then inserted in the position of Fig. 1 with the clamp against the wires lying in the conical bore of the lower part of the contracting unit, and the gripping head 9 is advanced to hold the cable in this position. The cap 22 of the contracting unit is applied to embrace the broomed wires.

The screw 34 is then operated to pull the contracting device outward to substantially the position of Fig. 2 where the mouth of the opening 26 in the contracting device is carried beyond the ends of the wires. In this movement the wires are pressed close together as they pass through the narrow end of the bore 26. In the final position the wires are held substantially straight (Fig. 2).

The next step is to insert the ring 52. The two halves of it are placed together and its tapered end is introduced into the flared opening in the contracting unit 19. Its inner edge is slightly beyond the outer ends of the wires, when it is pushed home into the member 19.

The socket is then placed in the machine and the cross head 31 brought up against it by a partial operation of the screw 34. A further operation of the screw 34 pushes the socket 39 into overlapping engagement with the flange on the outer end of the ring 52. This is the position of Fig. 2 and we are ready now for the step of passing the ends of the wires into the socket.

The screw 34 is now operated to push the contracting member 19 and the cross head 31 inward. The relation of the parts 19, 52 and the socket 39 is maintained during this move-

ment. When the movement begins, the ends of the wires first enter the flared opening in the ring 52 and are thus guided into the cylindrical bore thereof and into the bore of the socket. As the movement progresses, the ends of the wires pass into the socket and are released from confinement by the unit 19 and the ring 52.

The guiding ring 52 serves an additional purpose which is peculiarly advantageous. Its frictional engagement with the wires as it passes over them gives them a set or tendency to deform such that as they emerge into the bore of the socket they naturally bend outward from the center and thus effect an automatic separation from each other.

The outer portion of each wire is compressed longitudinally by its frictional engagement with the guiding ring, so that as soon as the wire is free the longer inner side of it expands and produces an outward bend. In most cases this action is sufficient to avoid the necessity of any subsequent manipulation of the ends of the wires within the socket.

When the wires have passed into the socket a sufficient distance to ensure their retention, the cap 22 of the unit 19 is unbolted and removed, leaving the wires resting in the member 20. The split ring 52 falls off or is removed readily by hand. This position is shown in Fig. 3. The cable is then released from the gripping holders 3 and 9 and the end bent up to a vertical position and the socket slid down to rest on the clamp 17 as in Fig. 3a. The ends of the wires should then extend practically to the outer end of the bore of the socket. If too long they are, of course, easily cut off. The socket and cable have to be held in this vertical position, of course, in order to pour in the zinc.

When the zinc is solidified, the clamp may be and generally will be removed. The untwisted wires should be distributed fairly evenly across the bore of the socket. They should also be clean. In this work it is common to clean the wires both before and after passing them into the socket to remove oil, grease and dirt.

The bore or opening in the socket or tip may be of various shapes other than the conical shape illustrated; the only essential being that it must be enlarged toward the outer end. And various other motive devices than the screw 34 may be employed in accordance with the weights and forces involved, and other circumstances.

The contracting unit 19 serves the purpose of first contracting or pressing the wires together, and then of holding or confining them to permit the application of the tip. The ring or unit 52 serves to confine the ends as they emerge lengthwise from the unit 19 and serves particularly as a guide to introduce them while thus confined into the small end of the tip opening; and serves also to impose upon the wires a tendency to bend outward as soon as they are released within the socket.

The separate instrumentalities of the machine may be varied and the functions of one or more of them may be served by separate tools or apparatus, or may be accomplished by hand. That is to say, the means for applying a tip to such untwisted ends of a cable may be used with various other devices than that described for holding the untwisted ends together to permit the application of the tip. The means for confining the untwisted ends as well as the means for guiding them into the tip and automatically spreading them therein, may be used for the ap-

plication of a tip by hand or by various other mechanisms than that described.

The invention also consists in the method of applying sockets or similar tips to wire cables or ropes. The conventional method has been to seize the cable (that is, bind it with wire at the end) or to untwist the wires and bind their ends with a piece of seizing wire, and to pass the seized end into the socket through the smaller end of the opening; thereafter removing the seizing and spreading the wires by hand. This has involved the use of a socket with a bore which at its small end is considerably larger (except in the case of hemp-center wire rope of which the center has been removed before socketing) than is required for the unseized end of the cable with the method of this invention.

Such an enlarged hole requires considerable calking with putty, clay or the like, around the cable where it enters the socket in order to hold the molten metal poured in; whereas, with the present method little or no calking is needed.

By untwisting the strands and wires in the open, and then inserting them without seizing into a socket with a hole closely fitting them, as in the present invention, much time is saved both in the untwisting and in the calking and pouring operations.

What I claim is:—

1. In a machine of the class described, means for gripping a cable near an end thereof which is to be provided with an anchoring tip, means for clamping the cable between the gripping means and its end so as to permit the brooming of the end of the cable and to restrict the length of the untwisted ends, means for contracting the untwisted ends and confining them close together and means for supporting a tip with an outwardly enlarged bore and moving the inner end of said tip over the confined wires and permitting the latter to expand within the bore.

2. In a machine of the class described, means for gripping a cable near an end thereof which is to be provided with an anchoring tip, means for clamping the cable between the gripping means and its end so as to permit the brooming of the end of the cable and to restrict the length of the untwisted ends, a contracting unit having a conical throat to receive the spread ends, means for advancing said unit outward so that the conical throat thereof will contract and retain the wires close together, means for supporting a tip having a bore with an enlarged outer end and feeding means having an abutment adapted to engage the tip and when moved inward to pass the tip over the confined ends of the wires so as to permit the latter to expand within its bore.

3. In a machine of the class described, means for gripping a cable near an end thereof which is to be provided with an anchoring tip, means for clamping the cable between the gripping means and its end so as to permit the brooming of the end of the cable and to restrict the length of the untwisted ends, said clamping means comprising a pair of separable collar sections, a contracting unit having a conical throat to receive the spread ends, means for advancing said unit outward so that the conical throat thereof will contract and retain the wires close together, means for supporting a tip having a bore with an enlarged outer end and feeding means having an abutment adapted to engage the tip and when moved inward to pass the tip over the confined ends of the wires so as to permit the latter to expand within its bore.

4. In a machine of the class described, means for gripping a cable near an end thereof which is to be provided with an anchoring tip, means for clamping the cable between the gripping means and its end so as to permit the brooming of the end of the cable and to restrict the length of the untwisted ends, a contracting unit comprising a pair of separable sections having recesses which form a throat of conical shape opening outward and adapted to embrace the untwisted wires, means for advancing said contracting means outward so as to contract and restrain the wires close together, means for supporting a tip having an outwardly enlarged bore and means for advancing the tip over the confined ends whereby the latter may expand within the bore. 80
5. In a machine of the class described, means for gripping a cable near an end thereof which is to be provided with an anchoring tip, means for clamping the cable between the gripping means and its end so as to permit the brooming of the end of the cable and to restrict the length of the untwisted ends, means for contracting the untwisted wires and confining them close together 85
- 20 in a recess of the contracting means, a guiding means comprising a sectional collar having an end adapted to seat in the outer end of the recess of the contracting unit, means for supporting a tip having an outwardly enlarged bore with its inner end in engagement with said guiding means and advancing said tip, guiding means and contracting unit inward to pass the tip over the ends of the wires and permit such ends to expand within its bore. 90
- 30 6. In a machine of the class described, means for gripping a cable near an end thereof which is to be provided with an anchoring tip, means for clamping the cable between the gripping means and its end so as to permit the brooming of the end of the cable and to restrict the length of the untwisted ends, a contracting unit having a conical throat to receive the spread ends of the wires, means for advancing said unit outward to bring said ends together and confine them, 95
- 40 guiding means comprising a sectional collar having its inner end adapted to enter the throat of the contracting unit, means for supporting a tip having an outwardly enlarged bore with its inner end engaging said guiding means and overlapping the same, and means for advancing the tip and guiding means and contracting unit inward to release the ends of the wires and introduce them into the bore of the tip and permit them to expand therein. 100
- 50 7. In a machine for applying an anchoring tip to the untwisted ends of the wires of a wire cable, the combination of means for confining the untwisted ends close together and means for applying a tip over the confined ends and simultaneously releasing them from the confining means so as to permit their separation as they enter the tip. 105
- 60 8. In a machine for applying an anchoring tip to the untwisted ends of the wires of a wire cable, the combination of means for drawing a confining device lengthwise over the untwisted ends to bring them close together and confine them and means for applying a tip over the confined ends and releasing them from the confining means so as to permit their separation within the tip. 110
- 70 9. In a machine for applying an anchoring tip to the untwisted ends of the wires of a wire cable, the combination of means for confining the untwisted ends close together, and means for applying a tip over the confined ends and for re- 115
- 75 moving said confining means progressively as the tip is advanced over the ends so as to permit separation of the ends within the tip. 120
10. In a machine for applying an anchoring tip to the untwisted ends of the wires of a wire cable, the combination of confining means adapted to engage the untwisted ends and to be advanced along the same to draw them close together and means for applying a tip over the confined ends and withdrawing the confining means progressively as the tip is advanced so as to permit the separation of the ends within the tip. 125
11. In a machine for applying an anchoring tip to the untwisted ends of the wires of a wire cable, guiding means through which the ends pass and are guided into the tip. 130
12. In a machine for applying an anchoring tip to the untwisted ends of the wires of a wire cable, means for pressing and holding close together the untwisted ends and a guide for directing the untwisted ends into the tip. 135
13. In a machine for applying an anchoring tip to the untwisted ends of the wires of a wire cable, a confining ring adapted to press together and to guide the ends of the wires and to be brought into overlapping engagement with the tip at its inner end so that by moving the tip and ring together along the cable the wire ends are freed from the ring as they pass into the tip. 140
14. In a machine for applying an anchoring tip to the untwisted ends of the wires of a wire cable, the combination of a contracting and confining means adapted to embrace the untwisted ends and by an outward movement to contract and confine them close together and a guiding and confining means engaging said contracting and confining means and extending beyond the outer face thereof, said guiding means being adapted to enter into overlapping engagement with said tip so that by movement of said parts inward the untwisted ends of the wire are released from confinement and guided into the bore of the tip and permitted to expand therein. 145
15. The method of applying an anchoring tip to a wire cable which consists in untwisting the ends of the wires, confining the untwisted ends, introducing them into the tip and releasing them during such introduction and finally fixing them within the tip. 150
16. The method of applying an anchoring tip to a wire cable which consists in untwisting the ends of the wires, holding the cable in shape at the desired distance from the end, confining the untwisted ends, introducing them into the tip and allowing them to expand during such introduction and finally fixing them within the tip. 155
17. The method of applying an anchoring tip to a wire cable which consists in applying a confining means to the untwisted wires and drawing it toward the end so as to bring the wires close together, applying a tip to the untwisted ends and confining device, allowing the untwisted ends to spread within the tip and fixing them therein. 160
18. The method of applying an anchoring tip to a wire cable which consists in pressing the ends of the untwisted wires together in a confining ring, bringing the tip into overlapping engagement at its inner end with said ring and moving the tip and ring together along the cable to free the wire ends from the ring as they pass into the tip. 165
19. The method of applying an anchoring tip to the ends of the wires of a cable which consists in forcing the ends of the wires while approxi- 170

5 mately parallel to the cable axis through a confining guide and thence into the small end of the bore of the tip having its outer end enlarged with the wires in close frictional engagement with the 5 guide so as to impress a set on the wires causing them to spread outward automatically when they are released within the bore of the tip.

10 20. In a machine for applying an anchoring tip to the untwisted ends of the wires of a wire cable, a confining and guiding ring adapted to

closely fit the ends of the wires in a position approximately parallel to the cable axis and means for forcing them through said ring and guiding them therefrom directly into the bore of a tip, the ring engaging the wires with a frictional engagement which is adapted to impose a set on the wires and cause them to spread outward automatically when they are released from the tip. 80
